AIRSHIP

William Noelle, Chicago, Ill.

Application February 17, 1933, Serial No. 657,203

16 Claims.

(Cl. 244—2)

This invention relates to air-ships.

Particular objects of the invention are:

To provide an air-ship of new and novel construction, which combines the safety and carrying capacity of lighter-than-air ships, with a mobility comparable, in a measure, with that of a usual air-plane:

To provide a frame for an air-ship of novel construction, which will impart great strength and rigidity to the ship, but will, at the same time, be relatively light in weight, as compared with any air-ships of which I have any knowledge;

To provide an air-ship rendered buoyant by gas which is lighter than air, as helium gas, contained in gas-bags confined in different compartments or bents defined by the framing of the ship:

To provide a suitable envelope or covering applied to the frame of the ship to enclose and protect the gas bags or containers for the gas:

To provide for conveniently applying and removing said protective covering or envelope:

To provide means for controlling the flight of the ship whereby the ship will maintain a substantially "even-keel" in flight and, also, in taking-off and in landing:

To provide an air-ship of the type specified, equipped with commodious and accessible cabin accommodations for passengers; and

To provide improved landing gear, which may conveniently be adjusted for landing the ship either on land or water.

To effect the objects thereof, an air-ship embodying my invention and improvements comprises the various features, combinations of features and details of construction hereinafter described and claimed.

In the accompanying drawings, in which the invention is fully illustrated,

Figure 1 is a side elevation of an air-ship embodying my invention and improvements, showing the landing gear adjusted for landing on a solid surface.

Figure 2 is an enlarged end elevation of the ship from the left side of Fig. 1.

Figure 3 is a somewhat enlarged side view substantially the same as Fig. 1, but with the outer protective envelope or covering removed and without the cabin.

Figure 4 is a transverse sectional elevation on the line 4—4 of Fig. 3, with parts rearward from the plane of section shown in diagram.

Figure 5 is an enlarged top plan view of one

member of the landing gear from the position 5—5, Fig. 3.

Figure 6 is a vertical longitudinal, central sectional view of an air-ship embodying my invention and improvements.

Figure 7 is a somewhat enlarged transverse, sectional view on the line 7—7 of Fig. 6, with parts omitted.

Figures 8 to 14, both inclusive, are enlarged fragmentary views showing structural details.

Figures 15 to 17 are enlarged views illustrating certain operating details.

Figure 18 is a side view of a modified form of frame, particularly designed and adapted for use in the construction of relatively large ships;

Figures 19 and 20 are enlarged sectional views on the lines 19—19 and 20—20, respectively, of Fig. 18.

Describing the invention with reference and referring in the first instance to Figs. 1 to 17, both inclusive, an air-ship embodying my invention and improvements, designated as a whole A, consists of a rigid frame designated as a whole B, gas bags or containers designated collectively C, a protective envelope or covering D, particularly designed and adapted for enclosing said gas bags and protecting them from injury, landing gears, comprising co-operating units, each designated as a whole E, said units being arranged in transversely aligned pairs or sets on opposite sides of the ship and comprising a plurality of such pairs or sets—preferably two—positioned, respectively, substantially equal distances on opposite sides of the longitudinal center of the ship. The foregoing elements will now be described in detail.

In what I now consider to be preferable construction, the frame B comprises a longitudinal, centrally disposed member designated as a whole b, and transverse frames—comprising substantially duplicate frames arranged symmetrically at opposite sides of the longitudinal center of said frame member b. As shown, there are eight such transverse frames designated, respectively, b', b², b³ and b⁴, duplicate frames at opposite ends of the ship being designated by the same reference characters.

In the preferable construction shown, the frames b—b⁴ are of the same construction, as nearly as may be, differing only in size, each thereof comprising members 1 which are preferably tubular, thus combining lightness with requisite strength, the inner ends of which are secured to the longitudinal frame member b by

fittings 2, as clearly shown in Fig. 14 of the drawings.

As also appears, see particularly Figs. 3, 6 and 14, said longitudinal frame member b is a composite structure, consisting of tubular sections 3, 4, 5, 6 and 7 of different diameters, rigidly secured together one within the other and in spaced relation. As shown, duplicate frames b' — b^4 at opposite ends of the frame B are rigidly secured to 10 the fittings 2 and the ends of said tubular sections, respectively, are spaced from and rigidly secured to the next adjacent inner tubular section by sleeves 8 on the fittings 2, which extend 15 between the ends of outer tubular sections and the next adjacent inner tubular sections and are rigidly secured to both thereof, preferably by brazing or welding, as also clearly shown in Fig. 14.

Both ends of the inner tubular section 7 project 20 beyond the ends of the next adjacent outer tubular section 6 and secured to the ends thereof by brazing, welding or other suitable means, are anchor caps 9, which form the extreme ends 25 of the frame A of the ship, and the function of which will presently be described.

Continuing the description of the transverse frames b' — b^4 , said frames—in addition to the members 1, also comprise members 10 which, also, 30 are preferably tubular and extend parallel with different members 1 and are rigidly connected to and rigidly connect the same and also each other, thus forming frames of great strength, lightness and rigidity. As shown, said frame members 1 and 10 are thus rigidly connected by fittings 11 having off-set bores 12, as clearly shown in Fig. 11.

As shown, the exterior of the ship is polyhedral in shape and in order that it may be balanced 40 and may present a symmetrical appearance, the radial distances from the axis of the longitudinal member b to the outer ends of the members 1 and 10 of the frames b' — b^4 , respectively, is the same and the angles defined by lines connecting 45 said points in the planes of said frames, respectively, are equal to each other.

In accordance with the invention, also, the outer ends of corresponding members 1 and 10 of each transverse frame b' — b^4 are connected fore and aft with each other and also with the anchor caps 9 secured to opposite ends of the longitudinal frame member b of the ship, by cables 13, and the outer ends of the members 1 and 10 of each frame b' — b^4 are connected transversely by cables 55 14. As shown, the cables 13 and 14 are not continuous from end to end of the ship, but consist of separate sections connected to the end anchor caps 9 and to anchor caps 15 secured to the outer ends of the frame members 1 and 10. As shown, 60 the anchor caps 9 are made in the form of disks and formed thereon are lugs 16 which are arranged in pairs at diametrically opposite sides of said disks and comprise two such pairs arranged at right angles to each other, said lugs being provided with eyes for making cable 65 connections thereto. Said caps 15 are rigidly secured to the outer ends of the frame members 1 and 10, preferable means for this purpose consisting of shanks or projections 17 thereon 70 which are fitted into the openings in the ends of said frame members and brazed, welded or otherwise secured therein. In installing said caps 15, care should be taken that the eyes in one set of lugs 16 shall align with the line of tension of the cables 13 which extend lengthwise

of the ship, and with the eyes of the other set or pair of lugs into which the transverse cables 14 are connected, in the planes of the different frames b' — b^4 and in symmetrical relation to the members 1 and 10 in which they are secured, respectively. 5

With the construction shown, the shanks of the caps 15 secured in the frame members 1 are substantially of the shape shown in Figs. 12 and 13, with the shanks 17 extending axially of the disk portions thereof, while the shanks of the caps 15 secured in the frame members 10 extend at an angle to the disk portions of said caps, substantially as shown in Fig. 13^a of the drawings. However, with the relation shown in the drawings, see particularly Fig. 4—in which the different frames b' — b^4 comprise frame members 10 which are symmetrically disposed with relation to the radial frame members 1 and are all of the same length, the inclination of the shanks 17 of the anchor caps 15 secured thereto, respectively, will be the same and substantially as shown in Fig. 13^a. Thus, with the construction shown in Fig. 4, only two different forms of anchor caps 15 will be required. 25

As shown, also, the end anchor caps 9 are substantially mushroom shaped and are recessed, as shown, to form interior ledges or shoulders 18, which, as shown, extend entirely around said caps and are reinforced or strengthened by ribs 19 which connect said shoulders with the body portions of said caps, and to provide for making cable connections to said caps, said caps are provided with holes 20 formed through the ledges or shoulders 18 between the strengthening ribs 19. 30 35

Also, in what I now consider preferable construction, the cables 13 are anchored to said caps by means of headed bushings 21 inserted through the holes 20 so that the heads thereof will rest against the interior ledges or shoulders 18. Formed on each cable to be anchored to said end caps 9 are heads 22 and, after the bushings 21 have been inserted into position in said caps, the cables are inserted through the holes in said bushing from the inside in position to rest in contact with interior ledge or shoulder 18. As shown, the caps 9 are secured to the ends of the inner tubular member 7 of the longitudinal frame member b by brazing or welding the ends of said tubular members in fixed engagement with sockets or recesses 23 formed in said caps, and for convenience of construction, the cables 13 are connected to the end caps 9 before said caps are secured to the longitudinal member b . 40 45 50

The frame members b' — b^4 having been assembled, the cables 13 and 14 are applied to connect the outer ends of the frame members 1 and 10 with each other, longitudinally, and also with the end anchor caps 9, and, also, to connect said frame members 1 and 10 with each other transversely, attachment of said cables being made directly to the eyes in the lugs 16 of the anchor caps 15, and to the holes 20 in the end caps 9. Said cables are then drawn taut and fastened. 60 65

As best shown in Figs. 6 and 7, the frame B of the ship is divided transversely into separate compartments by the transverse frames b' — b^4 which, however, are in open communication with each other—and confined in said compartments, respectively, are gas bags C, which are so shaped and proportioned that when said gas bags are inflated, they will fill the spaces or compartments in which they are positioned. In actual practice, said gas bags will be supported out of contact 70 75

with said transverse frames b' — b^4 which might puncture or tear said bags—by nets made of cord or other soft, pliable material, supported on said transverse frames but in spaced relation thereto. Said nets are not shown in the drawings but can readily be supplied by skilled mechanics without the exercise of invention.

The gas bags C may be made of any usual or desired material suitable for the purpose and can readily be supplied by manufacturers familiar with such structures, without the exercise of invention. Said gas bags necessarily will be provided with holes or passageways c which extend lengthwise through them and are arranged to receive the central longitudinal frame member b. As shown, the passages in the different gas bags are in substantial alignment with each other and form a continuous passageway lengthwise of the ship through said gas bags. For reasons presently explained, transverse passageways c', substantially similar to the passages c, extend from said passages c through certain of the gas bags C, to the outer sides of the ship, being positioned substantially symmetrically at opposite sides of the longitudinal center of the ship. In practice, to insure passageways or openings c, c' of full contemplated size and to prevent damage to the gas bags C by persons using said passageways, expansion of said gas bags into said passageways— which would contract and tend to close them—said walls are protected by and their full size maintained, by walls of suitable sheet material, as sheet aluminum or wood veneers, which, conveniently, may be supported on the structures of the walks 26, 26', presently described. Such supporting walls are not shown in the drawings, but can readily be supplied by skilled mechanics without the exercise of invention.

Collapse of the gas bags C, when deflated, is prevented by attaching them to frame members 1 and 10 of the frames b' — b^4 which define the compartments in which said gas bags are mounted, respectively, said means consisting, as shown, see Figs. 7 and 8, of straps and buckles 24 and 25 attached to said bags and adapted to be connected over or across frame members 1 and 10. Said gas bags will be equipped with any usual or desired apparatus for inflating and deflating them. Apparatus for the purpose is old and well known and can readily be supplied by mechanics familiar therewith, without the exercise of invention and, accordingly, such means is neither herein shown nor described.

As best shown in Fig. 7, a walk 26 is supported within the passage c and extends substantially the entire length of the ship, being shown as hung from the upper transverse frame members 10 of each frame b' — b^4 , by suspension members 27, and supported within the transverse passageways c' are walks 26' which form lateral extensions of the longitudinal walk 26. Preferably, also, the walk 26 will be connected to the frame member b so as to prevent lateral swinging movement of said walk relative to other parts of the ship—particularly the adjacent walls of the gas bags C which define the passages c. Simple means for thus preventing such swinging movement consists of light cables which extend around the member b, the ends of which are attached to the walk 26 at opposite sides of said member b, as shown at 28, Fig. 7.

To reduce wind and other atmospheric resistance to movement of the ship, the frames b' — b^4 at both ends of the ship from the central section between the frames b' , are progressively

and symmetrically smaller, the relation being such that opposite ends of the ship will be similarly tapered.

The frame B of the ship having been erected and the gas bags C installed, the protective covering or envelope D is applied to the ship outside of the frame B and gas bags C. Said protective covering preferably will be made of suitable fabric, as cotton duck, which has been impregnated with rubber to render the same air and water tight and practically inelastic. In order to shape said envelope or covering to that of the ship, said material is cut into sections which conform in size and shape to the different sides of the ship, the edges of said sections being connected by suitable means, as zippers, thus rendering it easy to adjust said protective covering to and remove it from the ship.

As shown, the extreme ends of said envelope or covering consist of unitary hood sections 29, 20 which are proportioned to fit snugly over the ends of the ship, which are quite sharply tapered, said hoods being made of substantially non-stretchable fabric, as cotton duck, which may be impregnated with rubber, if desired, thus providing a secure anchorage for the envelope or covering of the ship at both ends thereof.

In accordance with the present invention, the inherent buoyancy of the ship due to gas contained in the gas bags C, is supplemented and increased by the use of wings similar to those of air-planes. As shown, see particularly Figs. 1, 2 and 3, these comprise a wing or plane 30 secured in fixed position at the front of the ship, and other adjustably mounted wings 31 and 35 32, arranged in front and rear transversely aligned pairs on opposite sides of the ship and which are designed to facilitate maneuvering both in taking off and landing, said wings, also, being so proportioned and arranged that they will exert a substantially equal lifting action, thus tending to maintain the ship on an "even-keel" in flight.

As shown, the wings 31 and 32, respectively, are mounted to turn on extensions of the horizontal frame members 1 of the frames b^2 at opposite ends of the ship and are adapted to be controlled by a pilot stationed in the pilot house indicated at F at the extreme forward end of the ship, as best appears in Fig. 6, and, in Figs. 3 and 15, 50 I have indicated, more or less diagrammatically, control mechanism for manipulating said adjustable wings, which may exemplify any usual or desired means for the purpose, such as can readily be supplied by persons skilled in the art 55 without the exercise of invention. As shown, said control mechanism consists of double bell-crank levers 33 and 34, respectively pivoted in pairs to opposite ends of transverse shafts 35 and 36, each of said bell-crank levers comprising a lever arm 60 37 which extends at right angles to the other arms thereof, and is arranged in line with the pivots thereof, said arms 37 being connected by links 38 with the ends of a wing 31 or 32 remote from the pivot of said wing, said links 38 being pivotally connected both with the lever arms 37 and the wings 31 or 32 to which they are applied, respectively.

As further exemplifying suitable control means for operating the wings 31 and 32, means are shown adapted for turning the bell-crank levers 33 and 34 pivotally to bank or flatten said wings consisting, as shown, of a sheave or drum 39 secured to a shaft 40 rotatably mounted in a fixed frame 41 in the pilot house F, an operating lever 75

- 42 secured to said shaft, a cable 43 adjusted to the sheave or drum 39 and anchored thereto, opposite ends of which are secured to opposite ends of the bell-crank levers 33 and 34, whereby turning movement of said sheave or drum will impart corresponding pivotal movement to said bell-crank levers 33 and 34, and to the shafts 35 and 36 to which they are secured, respectively, which will operate in an obvious manner to bank or flatten the wings 31 or 32 as the bell-crank levers are turned in one direction or the other, as the case may be.
- To provide for turning the ship and changing the direction of its flight, the means for controlling the flight of the ship also comprises rudders mounted at the stern of the ship so as to be pivotally adjustable and which comprises sets or pairs of rudders arranged at right angles to each other, the relation being such that when the ship is on an "even-keel", said pairs of rudders will be disposed in substantially horizontal and vertical planes, respectively, and the rudders of each pair or set being arranged on opposite sides of the ship.
- In Figs. 16 and 17, in which I have shown, diagrammatically, the arrangement and manner of mounting said rudders, 44 and 45 designate, respectively, the vertically and horizontally disposed sets or pairs of rudders, each of which is mounted directly on the projecting rear end of the frame member 7 by substantially similar means which will now be described. Being similar, a description of one thereof will apply equally to both and to save repetition, the description will, therefore, be in the singular. As indicated in said Figs. 16 and 17, each set or pair of rudders is secured to posts 46 so as to turn therewith. Said posts are fitted to turn in bearings formed in members 47 forming parts of a frame secured to said member 7, indicated in Fig. 17. The inner ends of said posts are rigidly secured to the flat sides of what may be described as an elliptical yoke 48, which surrounds the member 7 in spaced relation thereto, and formed on the inner ends of said posts are studs 49 which are rotatably fitted to pivot bearings formed in a collar 50 secured to said member 7 as indicated at 51, the relation being such that said posts will extend substantially at right angles to the major axis of said yoke 48. With the described construction, it is obvious that rocking movement of the yoke 48 on its minor axis will impart turning movement to the posts 46 with the rudders secured thereto, in one direction or the other, as the case may be.
- In accordance with the invention, also, rocking movement is adapted to be imparted to said yoke 48 by means substantially similar to the means for turning the bell-crank levers 33 and 34 pivotally, shown diagrammatically in Fig. 15 and heretofore described. Said control means may exemplify any desired or approved form of control means and can readily be supplied by mechanics and engineers familiar with such structures without the exercise of invention.
- In flight, the ship is adapted to be propelled by engines indicated at 52 and 53, the engine 52 being mounted on the fixed front wing 30 and the engines 53 on the adjustable wings 31 and 32, in accordance with usual or desired practice. Engineers and mechanics familiar with such mechanisms can readily install said engines without the exercise of invention and it is, therefore, deemed unnecessary to either show or describe the same in detail.

In accordance with the present invention, also, my improved air ship is equipped with landing gears of new and novel construction, arranged for setting the ship down either on land or water.

To effect the object of the invention as it relates to providing landing gear whereby the ship may be "set-down" either on land or water, I will first describe in detail the construction of each landing gear unit E, and will then describe the manner of mounting and manipulating said units in accordance with my invention to effect this object.

All of said units are substantially similar in construction and a description of one thereof will apply equally to the others and the description of said unit will, therefore, be in the singular. In what I now consider preferable construction, see particularly Fig. 5, each landing gear unit E consists of a pontoon 54 and a wheel 55 mounted at opposite ends of a frame designated as a whole 56, comprising a longitudinal beam or bar 56, pinned or otherwise secured intermediate its ends between a pair of spaced lugs 57 on the top side of the pontoon 54 adjacent its rear end, and a transverse member 58 rigidly secured to the front end of same beam or bar 56, formed at opposite ends of which are lugs 59 pinned or otherwise secured between spaced pairs of lugs 60 on the pontoon, and rotatably mounted in a yoke 61 at the rear end of the beam 56 is a wheel 62, preferably a pneumatic wheel. In what I now consider preferable construction, the pontoon 54 is made hollow and gas and water tight and conforms substantially in shape to the wings 31 and 32. As installed for use, said pontoon will be filled with gas like that used for filling the gas bags C which, being lighter than air, will increase the buoyancy of said pontoon and to an extent, will assist in sustaining its weight when in the air.

As previously stated, the landing gear units E are arranged in transversely aligned pairs or sets on opposite sides of the ship A and comprise a plurality of such pairs, as shown two pairs positioned, respectively, substantially equal distances at opposite sides of the longitudinal center of the ship.

As shown, the longitudinal beams or members 56 of the frame e of each pair of landing gear units E are connected at approximately their longitudinal centers by a shaft or rod 63 which is rotatably fitted to sleeves 64 connected in fixed relation to rigid parts of the frame of the ship by struts 65, 66 and 67, the lower ends of said struts being brazed, welded or otherwise secured into flanged openings 68 on the sleeves 64 and their upper ends, respectively, being secured to extensions of the horizontal members 1 of the transverse frames b¹, b² and b³ of the ship's frame B. As described, it is obvious that the shafts or rods 63 to which the landing gear units E are secured, will be rotatably mounted in fixed positions relative to the frame B of the ship, and that the different landing gear units E will turn with said shafts.

In accordance with the invention, the beams or bars 56 of the landing gear units E are adapted to be turned pivotally to raise or lower either end thereof by means accessible for operation by a person on the ship proper A. As shown, said means consists of drums 69 rotatably mounted on relatively fixed frames 70, see Fig. 4, positioned on opposite sides of the frame B of the ship, means for rotating said drums in both directions consisting, as shown, of worm gears 71 mounted on said frames 70, adapted for manual

operation, and cables 72 anchored to the drums 69, opposite ends of which are connected to the beams 56 at substantially equal distances on opposite sides of the shafts 63 and in such relation thereto as will provide adequate leverages for turning said beams pivotally.

Also, to provide for raising and lowering the corresponding ends of the beams 56 of connected pairs of landing gear units E simultaneously and 10 by a single person, the actuating shafts of the worm gears 71 applied to each pair of said units E are connected, as by chain belts 73 adjusted to sprocket wheels 74 secured to the drum 69 of both worm gears, whereby rotation of either of 15 said worm gears will impart rotation to the other in the same direction.

In landing on the ground, the drums 69 will be turned in the proper direction to raise the pontoons 54 and to lower the wheels 55 of the landing gear units E, while in alighting on water, 20 said drums will be turned in the proper direction to raise the wheels 55 and to depress the pontoons 54.

Also, to minimize shock in landing, shock absorbers, indicated at 75, are connected into the 25 cables 72 between the drums 69 and the points of attachment of said cables to the beams 56. Shock absorbers suitable for the purpose can be purchased commercially or can readily be supplied by mechanics familiar with such devices 30 and it is, therefore, deemed unnecessary either to show or describe the same in detail.

In accordance with my invention, the weight 35 of the ship will somewhat exceed the buoyancy of the gas contained in the gas bags C and in the pontoons 54, if inflated, the ship being dependent upon the lifting power of the wings 30, 31 and 32—under the propulsion of the engines 52 and 53—to cause it to take-off and to sustain it in 40 the air during its flight, the ease of the take-off and the rapidity of the ascent depending to a large extent on the balance between the weight of the ship, including any load, to the lifting power of the gas with which the gas bags C are charged. Obviously, the more delicate the balance, the more rapidly the ship will take-off and 45 the faster it will climb.

In Figs. 1, 2 and 6 of the drawings, I have indicated diagrammatically, a cabin designated G, 50 attached to and suspended from the transverse frame members b' of the frame of the ship, and have indicated at 76 a ladder which connects said cabin with the passageway c which extends lengthwise of the ship, the intervening gas bag C being provided with a wall or passageway 77 for said ladder. Also, the ship is equipped with 55 a boarding and landing ladder pivotally connected to the floor of the ship and, in flight, arranged to be swung up into a recess formed in the bottom of the cabin, as indicated at 78, Fig. 6.

For ships of appreciably larger size than that for which the frame construction shown in Figs. 1 to 17 and heretofore described, are designed, my invention contemplates a modification of the 60 frame structure shown in said Figs. 1 to 17, with a view to imparting adequate strength to the frame to enable it to withstand the greater stresses to which it will be subjected in use.

In accordance with this modification, instead 65 of a single composite longitudinal frame member b, I contemplate a construction comprising a plurality of such composite longitudinal members—as shown 6—including two arranged centrally of the ship, one at each end—having a 70 common inner or core member which is contin-

uous from end to end of the ship, and four other composite frame members arranged symmetrical around the central longitudinal frame member and in spaced radial relation thereto.

Said frame also comprises frames substantially similar to the frame b'—b⁸ of the frame structure shown in Figs. 1 to 17, which, in accordance with the present modification are rigidly connected to and rigidly connect the ends of different tubular sections of different radially arranged composite 10 frame members, said connecting means comprising tubular fittings provided with flanged sockets in which the ends of radiating members of said transverse frames are secured, preferably by brazing, welding or the like, and which also comprise spacing sleeves which are inserted between the ends of outer tubular fittings of said composite longitudinal frame members and the next inner tubular frame member and which are brazed, welded or otherwise secured thereto, thus 15 binding them rigidly together—all substantially as in the frame construction shown in detail in Fig. 14.

As shown, the outer ends of members of the different transverse frames are connected—both 20 longitudinally and transversely—by cables as in the construction shown in Figs. 1 to 17, heretofore described.

This modification, as shown in Figs. 18 to 20 in which b designates the different composite longitudinal frame members of the ship, b' to b⁸ corresponding transverse frames at opposite ends of the ship, 1 the members of the frames b, b' which are arranged in radial relation to the central longitudinal frame of the ship, 10 the frame members of the different frames b' to b⁸ which extend parallel with the frame members 1, 13 the cables connected to and which connect the outer ends of the members 1 and 10 of each frame b' to b⁸ and 14 the cables which connect said members 1 and 10 transversely.

In practice, I contemplate making the metal portions of the ship of duralumin or other comparable light, strong metal or alloy.

I claim:

1. In a frame for an air-ship, the combination of a longitudinal member consisting of a plurality of tubular sections of different lengths and diameters arranged in radially spaced relation one inside of another, means for rigidly connecting said tubular sections together to form a unitary structure, and transverse frames each comprising members rigidly connected to said longitudinal member and other members rigidly connected thereto and to each other.

2. In a frame for an air-ship, the combination of a longitudinal member consisting of a plurality of tubular sections of different lengths and diameters arranged in radially spaced relation one inside of another, means for rigidly connecting said tubular sections together to form a unitary structure, consisting of sleeves inserted between said tubular sections, respectively, and the ends of the adjacent outer tubular sections and rigidly secured to both thereof, transverse frames each comprising members rigidly connected to said longitudinal member and other members rigidly connected thereto and to each other.

3. The frame for an air-ship specified in claim 1, which also comprises cables which connect the ends of frame members of different transverse frames fore and aft of the ship and which are anchored to the ends of the longitudinal frame member.

4. The frame for an air-ship specified in claim 1, in which the ends of the frame members of each transverse frame are connected by cables.
5. The frame for an air-ship specified in claim 2, in which the sleeves which connect the tubular sections of the longitudinal frame member form parts of fittings provided with sockets in which the inner ends of the frame members of the transverse frames connect to said longitudinal members are secured.
- 10 6. The frame for an air-ship specified in claim 1, in which the longitudinal frame member is continuous from end to end of the ship and anchor members are secured to the ends thereof and also to the ends of the members of each transverse frame, and which comprises separate cable sections which connect anchor members secured to adjacent frame members both longitudinally and transversely.
- 15 7. A frame for an air-ship comprising a plurality of longitudinal frame members constructed substantially as specified in claim 1, comprising centrally arranged members having a common innermost member, and other longitudinal members spaced radially from said central member, the relation being such that the adjacent ends of said radially spaced and centrally disposed frame members will overlap.
- 20 8. A frame for an air-ship comprising a plurality of longitudinal frame members constructed substantially as specified in claim 1, comprising centrally arranged members having a common innermost member, and other longitudinal members spaced radially from said central member, the relation being such that the adjacent ends of said radially spaced and centrally disposed frame members will overlap, and transverse frame members connected to and which rigidly connect the overlapping ends of said longitudinal frame members.
- 25 9. A structural element for an air-ship consisting of a plurality of tubular sections of different lengths and diameters arranged in radially spaced relation one inside of another, and means for rigidly connecting said tubular sections together to form a unitary structure.
- 30 10. A structural element for an air-ship, consisting of a plurality of tubular sections of different lengths and diameters arranged in radially spaced relation one inside of another, means for rigidly connecting said tubular sections together to form a unitary structure, consisting of sleeves inserted between said tubular sections, respectively, and the ends of the adjacent outer tubular sections and rigidly secured to both thereof.
- 35 11. The structural element specified in claim 10 in which the sleeves which connect the tubular sections of the longitudinal frame member form parts of fittings provided with sockets for securing other frame members thereto.
- 40 12. The frame for an air-ship specified in claim 1, in which the means for connecting the transverse frames thereto comprises fittings secured to said tubular sections, respectively, provided with flanged recesses in which the inner ends of members of transverse frames are secured, and formed on which are sleeves proportioned to enter between the tubular members to which said fittings are secured, respectively, and the ends of the adjacent outer tubular members and which are rigidly secured to both thereof.
- 45 13. The frame for an air-ship specified in claim 1, the inner tubular member of which is continuous from end to end of the ship and the others are successively shorter, and which comprises means for rigidly securing the ends of outer tubular members to the next adjacent inner tubular members, respectively.
- 50 14. In an air-ship, the combination of a rigid frame provided with interior compartments, gas bags contained in said compartments, and a protective covering applied to the frame of the ship arranged to enclose said gas bags, the weight of the ship exceeding the buoyancy of the gas in the gas bags, a landing gear adapted for bringing the ship down both on land and water comprising duplicate sets of landing gears mounted on the frame of the ship symmetrically on opposite sides of its longitudinal center, each of said landing gears comprising a beam, a pontoon mounted at one end thereof and a wheel rotatably mounted at its other end, a shaft which connects the beams of transversely aligned landing gear units, means for rotatably mounting said shafts on the frame of the air-ship comprising sleeves provided with bearings to which said shaft is rotatably fitted, struts which connect said sleeves with rigid parts of the frame of the air-ship and means for turning said beams pivotally to raise and lower opposite ends thereof to depress either the pontoons or the wheels carried thereby into operating position, as desired.
- 55 15. The combination specified in claim 14, in which the pontoons are hollow and are gas and water tight whereby, in operation, they may be filled with buoyant gas.
16. The combination specified in claim 14, in which the means for turning the beams of the landing gear units pivotally comprise resilient shock absorbers.

WILLIAM NOELLE.
